UNITED STATES PATENT OFFICE.

PERRY O. BROWN, OF ST. VINCENT, MINNESOTA, ASSIGNOR OF ONE-HALF TO GUSTAF V. BACKSTROM, OF ST. VINCENT, MINNESOTA.

RAILROAD SWITCH.

Application filed July 11, 1925. Serial No. 43,016.

This invention relates broadly to an improved railway switch for universal use, and it has specific reference in one instance to an improvement in the switch itself, together with electrical and mechanical safety contrivances and appliances associated therewith in a novel manner to be hereinafter more particularly pointed out.

Briefly, the invention has reference to a structure wherein a side track is associated with a main track, together with an automatically operable switch cooperable with these two tracks whereby a train may automatically pass from the side track onto the main track, at which time the switch is automatically thrown to permit this to be safely accomplished. In this connection, it is to be stated that the switch is constructed in a manner to be shifted by the wheel flanges. Acting in conjunction, however, is an electrical safety appliance for aiding in throwing the switch at this time, and this safety appliance is in open circuit with the track and closed by the train itself. Means, preferably controlled from a suitable source of current, is utilized in association with said electrical safety appliance so that the switch may be thrown without the aid of the car wheel flanges in order that it may be properly positioned for allowing safe travel of a train, moving in the opposite direction, from the main track onto the siding.

In addition, the invention provides for another electrical safety appliance, disposed on the opposite side of the track and acting to automatically return and hold the switch in a close position. This safety appliance is in open circuit with the track and the circuit is closed by the train itself. A distinct feature of this appliance is that it embodies a normally closed circuit closer which serves to move the switch from a partially closed position to a fully closed position, and which is rendered inoperative in itself when the switch is fully opened.

The invention is further characterized by an arrangement of structural details which is an improvement upon inventions of this class, due to the fact that it is comparatively simple, practical in construction, and such that it may be incorporated in a conventional track system without requiring extensive alterations of the tracks, rails, and the like.

In the accompanying drawings forming a

part of this application, and in which like numerals are employed to designate like parts throughout the same:

Figure 1 is a top plan view of portions of a main track, a side track, and the improved switch, the arrangement of details being somewhat diagrammatic so that the general structure may be viewed as a unit.

Figure 2 is a detail view of an electrical contrivance forming a part of the invention.

Figure 3 is a similar view of another electrical contrivance.

Figures 4, 5, 6, and 7 are cross sectional views taken approximately upon the planes of the lines 4—4; 5—5; 6—6; and 7—7 of Figure 1 respectively.

Referring to the drawings in detail the reference characters 1 designate the rails of what is defined as the main track. These appear at both ends of the showing in Figure 1. The reference characters 2 designate the rails of the side track, frequently referred to as a siding. The improved switch intervenes between these two tracks, and the relatively movable parts or members of the switch are designated generally by the reference characters 3 and 4 respectively. In connection with the rails 1, at the left hand side of the drawing, attention is directed to the brace or supplemental guard rails 5 disposed in spaced parallelism with the rails 1.

These rails are connected together by bridle bars or adjustable connections 6 simulating ordinary turn-buckles. Adjacent the converging ball forming portions of the rails 1 and 2, and on the right hand side, is an additional guard rail 7. Moreover, duplicate bridle bar connectors 8 are employed between the switch members 3 and 4 to cause simultaneous operation of these members, and to permit any necessary adjustments of the same to be made. The member is pivoted to swing upon the vertical axis indicated at 9, while the member 4 is pivoted to swing upon the vertical axis 10.

Considering more in detail the rail member 3, attention is directed to Figures 6 and 7 wherein it will be seen that this member is in reality made up of two rails, each including a head, a web, and a base. A spacing bar is arranged between the web portions and is bolted in place as shown plainly in Figure 7. The base portions of these rails rest slidably upon a base plate bolted to the tie. This base plate is of a width slightly greater than the combined

widths of the bases of the rails and is of a length equal to the complete member. In some instances this member 3 may be referred to as a duplex or double rail stub, and by comparing it with the member 4, it is seen that it is considerably shorter in length. It is obvious that the ball forming portions of these two rails are intended to be selectively aligned with the corresponding portions of the rails 1 and 2, according to the course that the train is to assume.

Referring now to the switch member 4, it will be seen from Figures 4 and 5, that it comprises a single rail 15, and that this rail is relatively wide at its right hand end and tapers gradually to the right, while it tapers substantially to a knife-like edge, as at 15^a, at its opposite end. The right end is associated with a wing 16 formed integral with the base portion of the rail and constituting the means for connecting this rail with the aforesaid pivot pin 10. The double rails of the switch member 3 are distinguished from the rail 14 by the reference characters 12 and 13 as shown. It should be noted also from Figure 4 that the forward portion of this rail 14 is substantially right angular in cross section, and this right angular portion rests upon a relatively short base plate 14^a, bolted or otherwise fastened to the adjacent cross tie 15^a. This plate 14^a is of a length to accommodate the necessary movement of the rail 14.

The stem of a spring pressed plunger 17 is connected with the switch member 4. The outer end of this plunger is confined in an appropriately anchored casing 18 alongside of the track rail 2. These details form what is sometimes known in the art as a fly-back. Cooperating with this fly-back is an electrical safety appliance in the housing 19, this housing being suitably anchored on one of the cross ties. Confining attention more particularly to Figure 2, the construction of this electrical appliance may be more closely observed. As shown here, it comprises a pull rod 21 connected with the switch member 4, and having an armature head on its inner end cooperable with an electromagnet 22. Mounted on the rod is a right angular arm 23 carrying a spring pressed contact 24 adapted for coaction with the spaced contacts 25. The circuit wires are connected with the contacts 25 and the contact piece 24, which is relatively slidable, is adapted to bridge these contacts 25 to normally render this electro-magnet in open circuit with the track as will be hereinafter more plainly understood. Here, it might be stated that under certain conditions, these contacts 24 and 25 are exceedingly important. For instance, if the switch is only partly opened, the circuit in which the contacts are included will be in readiness to immediately close the switch fully as soon as

the circuit is closed by the train approaching the trip from the left. This electrical appliance, together with the mechanical device described, makes an automatic means for returning the switch to closed position and holding it in such position.

On the other side of the switch structure is the means for throwing the switch. This comprises, in one instance, a flexible chain 26 (see Figure 1) which is primarily used for throwing the switch by hand, the same being connected in any suitable manner to the base of the double rail stub or switch member 3. In addition, it comprises an electrical safety contrivance represented generally by the reference character 27, this same contrivance being also used for throwing the switch, by electricity, from a circuit control from a tower by means of an electric switch button. This contrivance serves also for holding the switch open when thrown mechanically by the flanges on the car wheels. More specifically, and as shown in Figure 3, this contrivance comprises a housing 28, a rod 29 having an armature head cooperable with the electromagnet 31. The magnet 31 in the housing 28 is included in what may be referred to as a double electric circuit, that is, a circuit which includes two parts, an automatic part controlled by the train, and a manually controlled part, operated preferably from a suitably located tower (not shown). This double circuit arrangement includes two sets of wires, the main wires designated by the reference characters 32 and subordinate wires designated by the reference character 32^a. Incidentally, the subordinate wires are connected with the main wires 32. Moreover, the subordinate wires 32^a are, in practice, connected with the battery or other suitable source of supply and they include a switch (not shown) which is preferably located in a tower alongside of the track, (also not shown).

The wires 32 connected with a separate battery, and in addition one wire connects with the rails of the track on one side and the other wire connects with the cross wire 35 between the track rails. The wires 32^a therefore form the tower circuit and the wires 32 form the train controlled track circuit. It will be evident, therefore, that the magnet 31 can be energized either through the medium of the wires 32 and 35 or through the medium of the wires 32^a, 32, and the tower switch. Therefore three different sources of operation are provided, the mechanical means 26 and the electrical means 27, which includes an automatic electrical part and a tower controlled part. The first named circuit on the opposite side of the track which includes the magnet 22 also includes current wires designated by the reference characters 33, these being associated with a source of supply and a wire 34

which is connected with the track rail. This provides a normally opened circuit. In all three instances, the separate circuits are connected with suitable and separate sources 5 of electrical energy or supply. Furthermore, it is clear that the circuits are, in two instances, closed, when the wheels of the train pass over the portions of the rails in which the wires 34 and 35 are connected. 10 A circuit is then completed through the wheels, axle, wire, etc.

From the foregoing, it will be seen that I have provided a novel switch between the spaced ends of the rails included in a main 15 track and a side track. The switch comprises a pair of differently constructed members of relatively different lengths which are connected together to operate in unison. The switch is normally closed, under the 20 action of the spring pressed plunger 17 and the electrical safety appliance 19. Under such circumstances, the train may traverse the main track as if no switch were present. Also, a train coming from the side track 25 onto the main track will serve to press the member 4 of the switch away from the relatively stationary part of the track, and in so doing will throw the switch so as to permit the train to get from the side track 30 onto the main track when traveling in a direction from right to left. In traveling to the opposite direction, the wheel flanges do not function, but the mechanical operating means may be used to throw the 35 switch by hand power, or the electrical safety contrivance 27, may be used, for throwing the switch over to allow a train to shift from the main track onto the side track. At this time, the electrical appliance 40 27 is operated by energizing the magnet through the circuit wires 32^a, and then 32, by closing a switch in a tower. If desired, an electric motor, compressed air, or other suitable power could be connected with the 45 chain 26 for operating it. It is obvious too, that when the switch is completely thrown over to open position by the magnet 31, a gap will occur between the contacts 25^b by the unbridging of the same by the contact member 24, thus rendering the electrical safety appliance on the other side inoperative 50 for the time being.

From the foregoing description, it is clear that I have evolved and produced a novel 55 switch for railway tracks possessing, among others, the following advantages. First, it provides a most satisfactory arrangement or combination of the movable switch rails, it being thought that the switch per se, is novel 60 in itself, owing to the particular construction of the double rail stub, and the especially shaped mono-rail forming the co-operating member on the other side. It should be noted that the mono-rail is constructed properly to bring about the desired

wedge action produced by the flanges of the car wheels in enabling the latter to shift the switch when the train is moving from the siding onto the main track, at which time the electrical appliance 27 aids in the 70 operation. Secondly, the invention serves to minimize the difficulties caused by snow, ice, and other foreign matter interfering with the effective operation of switches of this kind. Due to the fact that the switch 75 is normally closed, the accumulation of such elements between the main track and switch rails is avoided. Moreover, undue friction and resistance to the operation of the movement of the switch rails is reduced to a 80 minimum making the operation easy and with precision. Generally, it offers a mechanical and electrical means coacting in the proper manner to safeguard against dangers rising out of the operation of railway switches. It is to be understood, in connection with the electrical contrivance 27 that a source of current is included in the 85 wires 32, this being of a strength which energizes the magnet 31 to a degree to 90 render it insufficient to throw the switch unaided. It is the purpose of this particular circuit to simply aid in moving the switch to open position when it is acted on by the car wheel flanges 6. The current passing 95 through the wires 32^a, however, is from a source which is comparatively stronger, this being operated, as before stated, from a tower. The current here generated is sufficient in itself to energize the magnet 31 100 to a degree to operate or throw the switch entirely unaided. It is understood that in connection with the circuit through the wires 32, that this circuit is closed automatically by the car wheels, and axle of 105 the locomotive moving from the siding onto the main track, this end being accomplished when the train is within a few rods of the railway switch. The other circuit is used more particularly for throwing the 110 switch for trains approaching the same from the opposite direction.

No doubt, a careful consideration of the description in connection with the drawings will enable persons skilled in the art to 115 understand of the same. Therefore, a more lengthy description of the invention is thought unnecessary.

While the preferred embodiments of the 120 invention have been specifically described and shown, it is to be understood that minor changes coming within the field of invention claimed may be resorted to if desired.

Having thus described the invention, what 125 I claim as new and desire to secure by Letters Patent is:—

1. In a switch construction, a main track embodying spaced parallel rails having a gap existing between the adjacent ends, a side 130

track embodying diagonal rails connected with the adjacent parallel rails of the main track, one of the rails of the side track being connected with a remote rail of the main track, and bridging said gap on one side, and a switch located in said gap and embodying simultaneously movable members provided with ball portions adapted to be selectively aligned with the ball portions of the side rails or main rails as desired.

2. In a switch structure, a main track embodying spaced parallel rails having a gap existing between the adjacent end, a side track embodying diagonal rails connected with the adjacent parallel rails of the main track, one of the rails of the side track being connected with a remote rail of the main track and bridging said gap on one side, and a switch located in said gap and embodying simultaneously movable members provided with tread portions adapted to be selectively aligned with the ball portions of the side rails or main rails as desired, the tread portion of one of the members of said switch normally being in contact with the corresponding portion of the diagonal portion of the side rail bridging said gap.

3. In a switch of the structure described, a pair of spaced parallel switch rail sections connected together for pivotal movement, each of said sections embodying a base flange

having an upstanding web at the top of which is a tread portion, the cross sectional shape of the tread portion of one of said switch rail sections varying in width so that this tread portion is tapered toward its opposite ends.

4. In a railway switch structure of the class described, a relatively short section embodying spaced parallel rails adapted to be aligned at one end either with the ball portion of a main rail or the ball portion of a side rail, a second switch section of a length greater than the first named section, and connections between said switch sections.

5. In a railway switch structure of the class described, a pair of spaced parallel switch sections, one of which is comparatively long and the other one of which is comparatively short, each of said sections being adapted to be pivotally mounted in a switch gap provided in a railway track, said long section comprising a tread portion which is decreased in width toward its free end to provide a knife edge, the butt end of said tread portion being also decreased in width toward the pivoted end, an attaching wing at the last named end of said long section and connections between said switch sections.

In testimony whereof I affix my signature.
PERRY O. BROWN.
